UNITED STATES PATENT OFFICE.

MOSES F. BAGLEY AND JOSEPH C. DAWSON, OF MOUNT VERNON, ILLINOIS.

STEAM-PUMP.

SPECIFICATION forming part of Letters Patent No. 291,021, dated January 1, 1884.

Application filed June 21, 1883. (No model.)

To all whom it may concern:

Be it known that we, MOSES F. BAGLEY and Jos. C. DAWSON, of Mount Vernon, county of Jefferson, and State of Illinois, have invented a new and Improved Steam-Pump; and we hereby declare the following to be a full, clear, and exact description thereof, reference being had to the accompanying drawings, making part of this specification, in which—

10 Figure 1 is a plan view of the pump. Fig. 2 is a vertical sectional view of the same. Fig. 3 is a vertical section on the line *y y* of Fig. 1. Fig. 4 is a side elevation, showing the steam-valve and conduction-pipes. Figs. 5, 15 6, 7, and 8 are details to be referred to.

Our invention relates to steam-pumps; and it consists in a cylinder, in which works a piston-rod having two pistons, and an intermediate reciprocating valve and proper ports, 20 whereby steam admitted alternately behind the pistons will raise and force water, as will hereinafter more fully appear by description in detail.

In order that those skilled in the art may 25 make and use our invention, we will proceed to describe the manner in which we have carried it out.

In the said drawings, A is a cylinder provided with a steam-chest, B, and steam-passages *a a*, leading from the steam-chest to the 30 ends of the cylinder and next to the heads C. A sliding valve, D, alternately connects the steam passages or pipes E with the ports *b b'*, the one disconnected with the steam-port being 35 always the exhaust-port, the exhaust-steam escaping through pipe *d*. The valve-rod *e* is, by means of a tappet, *e'*, thrown in proper time.

Across the center of the cylinder is secured 40 an abutment or brace, F, centrally pierced at *f* for the passage of the piston-rod G. The abutment F may be fastened by bolts through the sides of the cylinder, as seen at *g g*, or by any other desirable means.

45 Straddling the abutment F is a sliding valve, H, which controls the water-supply from the water-ingress pipe I. This valve consists of two heads, *h h'*, on opposite sides of the abutment F, and connected at their tops by a curved piece, *i*, and near their bottoms by narrow strips *i' i'*. The heads *h h'* are packed 50 to fit the cylinder water-tight, and have cen-

tral openings, *j j*, through which passes the piston-rod, so that the valve slides upon the piston-rod until one of the heads *h h'* brings 55 up against the abutment F.

In a horizontal line with openings *j j* the heads *h h'* are provided with openings *k k*, which serve alternately in pairs as ingress-ports for the water passing into the cylinder, 60 and act in a manner hereinafter described. The piston-rod is provided with two pistons, *L L'*, which are arranged at proper distances, to have them work in time with the proper stroke. 65

On top of the cylinder is a water-discharge chamber, N, having an air-chamber, M, and a discharge-pipe, O.

At the ends of the chamber N ports *l l'* communicate with the cylinder, and are arranged 70 at such a distance apart as to be alternately uncovered by the throw of valve H, and the ingress-pipe I for the water-supply always remains open between the heads *h h'*. (See Fig. 2.) Whenever the valve H, at the extreme of 75 the throw, brings up against the abutment F, the openings *k k* in the contiguous head of the valve are closed by said abutment. The ports *P P'* serve alternately as ingress and exhaust ports for the steam. 80

The operation is as follows, supposing that the cylinder between one of the pistons and one of the valve-heads *h h'* is filled with water raised on the last stroke by the vacuum: Steam is admitted behind the piston in the end 85 of the cylinder containing water, and as said piston begins to move it forces the contained water against valve H, and throws it against abutment F. This closes openings *k k* and opens the port next to the end containing the 90 water, which leads to chamber N, whereby the pressure of the steam on the piston forces the water into said chamber and out at pipe O. Meantime the movement of the other piston 95 passing away from the center of the cylinder creates a vacuum, which draws the water up ingress-pipe I, through openings *k k*, which are not against the abutment F, and into the cylinder, as shown by the arrows, Fig. 2, until it is filled. Then the tappet throws the 100 valve, and the reverse stroke is made, repeating the operation.

It is evident that any desired form of steam-valve or any desired tappet or form of ports

may be used without departing from the spirit of our invention.

Having thus described our invention, what we claim as new, and desire to secure by Letters Patent, is—

1. In a steam-pump, a cylinder provided with a steam-chest, a valve, and proper steam-ways, in combination with two pistons moving simultaneously, and an intermediate wa-

ter-way valve operated by the pressure on the water by each piston alternately, substantially as set forth.

2. The cylinder provided with ports $l l'$, and ingress-pipe I , in combination with valve H , provided with openings $k k$, and stationary abutment F ; all constructed, arranged, and operated as set forth.

3. The cylinder provided with ports $P P'$, $l l'$, and steam-chest having a main valve and proper steam-connections, in combination with the piston-rod, carrying two pistons, $L L'$, intermediate valve, H , having heads with openings $k k$, abutment F , ingress-pipe I , chamber M , and discharge-pipe O , all constructed, combined, and operated substantially as set forth.

MOSES F. BAGLEY.

JOSEPH C. DAWSON.
